UNITED STATES PATENT OFFICE.

LAMBERT A. SWANSON, OF SUPERIOR, WISCONSIN.

RAIL PLANER.

Application filed June 8, 1925. Serial No. 35,672.

To all whom it may concern:

Be it known that I, LAMBERT A. SWANSON, a citizen of the United States, and resident of Superior, in the county of Douglas and State of Wisconsin, have invented certain new and useful Improvements in Rail Planers, of which the following is a specification.

In recent years is has been quite common at coal docks, ore docks and similar places on the Great Lakes and in other parts of the country to provide automatic rail clamps attached to travelling cranes or bridges for the purpose of gripping the ball of the rail on which they move. These clamps are for the purpose of protection from accidental movement in case of sudden winds or tornadoes and necessitate maintaining a standard width on the rail ball.

After use for a considerable time the rail is apt to become somewhat deformed, and the ball thereof is uneven in width. The present invention is designed to provide a rail planer which may be attached to a travelling bridge of any suitable type and will plane the sides of the ball of the rail in order to bring the same back to standard width after it has become beaded or spread by use.

An object of the invention is to provide such a planer which will be simple in construction and efficient in operation, as well as relatively inexpensive to manufacture. The supporting rail is designed to carry tool holders in which are clamped tools which will engage the opposite sides of the ball of the rail and be held firmly in contact therewith by spring pressure. A movement of the bridge and tool holders along the rail will automatically plane off any projection or irregular portions and reduce the rail to its standard width.

Various detail objects of the invention will be apparent from the following description and appended claims.

In the drawings:

Figure 1 is an end elevation of the planer in operative position relative to a rail which is shown in section.

Figure 2 is a side elevation.

Figure 3 is a view on an enlarged scale of the lower end of one of the tool holders with the parts partially disassembled.

A suitable bridge member A is supported by wheels B, only one of which is shown,

which are adapted to travel along the rail C to be planed. This travelling support may be of any suitable character and driven by any suitable means. Attached to the bridge member A by bolts or other fastenings 1 are plates 2 through which passes a shaft 3 positioned in said plates in any suitable manner. Near one end of this shaft supports depending tool holder bars 4 which are suitably spaced apart on the shaft by a sleeve 5. Near the lower end there is threaded into one of the bars 4 a screw threaded bolt 6 provided with an adjusting nut 7. The head of this bolt bears against the other bar 4 and thus suitably spaces the two bars.

Also supported by the bridge A and attached thereto by fastening means 8 are two plates 9 through which passes a shaft 10 which lies at one side of the bars 4 and limits their movement in one direction so as to hold these bars in vertical position when the bridge member is travelling.

Adjacent the lower end of each bar 4, it is provided with a groove in which fits the planing tool 11 having a cutting edge 12. This tool projects beyond the face of the bar 4 and is clamped in position by means of a plate 13 through which pass screws or bolts 13' provided with nuts 14 by which the plate may be drawn firmly against the tool 11 and the latter thereby clamped immovable in operative position. The grooves in which these cutting members are located are in the face of the rail on the side toward which the machine moves when in operation. On the inner face of each bar 4 is fastened by screw 15 a thin plate 16 of hardened metal which contacts with the rail ball and prevents too deep a cut.

Passing transversely through the bars 4 is a rod 17 provided at each end with nuts 18. Adjoining each nut is a washer 19 and between each washer and the outer face of the bar 4 is positioned a very strong coil spring 20, the tension of which can be adjusted by varying the position of the nuts 18. In this manner the cutting tools are caused to engage the rail with the desired force. A roller 21 provided with a hardened bearing 22 is mounted on the rod 17 between the bars 4 and said roller runs upon the top of the rail. This prevents any accidental drop of the tool holders to a position lower than is desired.

It will be noted that the relative position of the bars 4 is determined by the members 6 and that the springs 20 will press the bars toward each other until the movement is limited by this member. The parts are so positioned that at the same time the hardened plates 15 will engage the sides of the ball of the rail. Since the roller 21 limits the downward movement of the cutting members it is evident that the cutting members are positioned exactly and by movement along the rail will plane the same to the desired standard width.

The length of the bars 4 and in fact the dimensions of the various parts will depend upon the type of bridge to which the planing member is attached and also upon the character of the rails upon which the operation is to be conducted. In general, it may be noted that the invention does not reside in the specific details or in the dimensions of the parts as these may be modified widely without departing in any degree from the spirit of the invention, which is to be regarded as limited only by the scope of the appended claims.

I claim:

1. A rail planer comprising a travelling support, tool holders carried thereby, tools carried by said holders and engaging opposite sides of the ball of the rail and spring means for pressing said holders and tools toward the rail.

2. A rail planer comprising a travelling support, tool holders carried thereby, tools carried by said holders and engaging opposite sides of the ball of the rail, spring means for pressing said holders and tools toward the rail and means for limiting the extent of said movement.

3. A rail planer comprising a travelling support, tool holders carried thereby, means for spacing apart said tool holders, tools carried by said holders and engaging opposite sides of the ball of the rail, and adjustable spring means for pressing the holders and tools toward the rail.

4. A rail planer comprising a travelling support, depending bars carried by said support, tools clamped in the lower ends of said bars and adapted to engage opposite sides of the ball of the rail, hardened members on the inner sides of the bars and adapted to engage the rail when planed to a standard width, and means for pressing said tools toward the rail.

5. A rail planer comprising a travelling support, depending bars carried by said support, tools clamped in the lower ends of said bars and adapted to engage opposite sides of the ball of the rail, hardened members on the inner sides of the bars and adapted to engage the rail when planed to a standard width, and adjustable spring means for pressing said tools toward the rail. 60

6. A rail planer comprising a travelling support, depending bars carried by said support, tools clamped in the lower ends of said bars and adapted to engage opposite sides of the ball of the rail, hardened members on the inner sides of the bars and adapted to engage the rail when planed to a standard width, adjustable spring means for pressing said tools toward the rail, and means limiting the downward movement of the bars. 70

7. A rail planer comprising a travelling support, depending bars carried thereby, tools carried by the lower ends of the bars and adapted to engage opposite sides of the ball of the rail, a transverse rod passing through the bars, and means on said rod tending to move the bars toward the rail. 75

8. A rail planer comprising a travelling support, depending bars carried thereby, tools carried by the lower ends of the bars and adapted to engage opposite sides of the ball of the rail, a transverse rod passing through the bars, means on said rod tending to move the bars toward the rail, and means carried by the rod and limiting downward movement of the bars. 80

9. A rail planer comprising a travelling support, a shaft carried thereby, tool supports on said shaft, a second shaft carried by said support and limiting the movement of the tool supports in one direction, means pressing said tool supports toward each other, and means limiting the extent of said movement. 90

10. A rail planer comprising a travelling support, a shaft carried thereby, tool supports suspended from said shaft, means for limiting the swinging movement of the tool supports in one direction, means pressing the tool supports toward each other, means limiting the extent of such movement, and means limiting the downward movement of the supports. 100

In testimony whereof, I have hereunto subscribed my name.

LAMBERT A. SWANSON.
